Application September 3, 1940, Serial No. 94,766

Term of patent 7 years

To all whom it may concern:

Be it known that we, Rolland C. Sabins and Averd Nelson, citizens of the United States, residing at Wisconsin Rapids, in the county of Wood and State of Wisconsin, have invented a new, original, and ornamental Design for Camp Stoves, of which the following is a specification, reference being had to the accompanying drawing, forming a part thereof.

In the drawing—

Figure 1 is a perspective view of a camp stove showing our new design;

Figure 2 is a front elevation of the stove;

Figure 3 is an end view of the stove; and

Figure 4 is a rear elevation of the stove.

We claim:

The ornamental design for a camp stove, as shown.

ROLLAND C. SABINS.
AVERD NELSON.
